UNITED STATES PATENT OFFICE.

JOHN WILLIAM NASMITH, OF MANCHESTER, ENGLAND.

BANDING MACHINE.

Application filed April 13, 1921. Serial No. 461,082.

To all whom it may concern:

Be it known that I, JOHN WILLIAM NASMITH, a subject of the King of Great Britain, residing at Leegate Heaton-Mersey, 5 Manchester, England, have invented new and useful Improvements in Banding Machines, of which the following is a specification.

This invention relates to apparatus for applying adhesive substances to bands of paper or other material to be afterward applied to boxes or the like, and the invention has particular reference to machines capable of being used for gluing strips of ornamental or decorative edgings or borderings to a main band before its application to the box. In my United States Patent No. 1,208,819, granted to me December 19, 1916, it is explained (page 3, lines 65 to 85) 20 that it is very desirable that the bordering strips should be placed on the machine in their proper relative positions to each other and to the main band to which they are to be attached.

25 The mechanism illustrated in Figures 5 and 6 of the said patent, comprises two gluing rollers and two stripping rollers operating in two separate glue tanks, with a gap between them through which the glued 30 edgings are passed and united to the main band A on the roller D. This arrangement has two draw-backs. The two pairs of rollers constitute a heavy load, the inertia of which has to be overcome by the starting 35 device every time the band is pulled forward, and whose momentum must be arrested by the catch when the pull ceases, and it is further very inconvenient to pass the 40 glued edgings through the gap between the tanks and unite them properly with the main band.

The object of the invention is, therefore, to provide improved means for gluing not only the underside of a band, but also to 45 transfer glue from the gluing roller to a portion of the upper surface of such band or bands and along one or both margins, and thus make it possible to glue both the main band and the strips, and unite the 50 three on a single gluing roller, instead of employing a pair of rollers and two tanks, thereby greatly simplifying both the machine and the work of the operator.

In order that the invention may be understood, two sheets of drawings are appended 55 in which,—

Figure 1 is a side elevation of so much of a machine embodying some of my improvements as is necessary to an understanding thereof, while other improvements form 60 the subject-matter of another application, Serial No. 309,467, hereinafter referred to.

Figure 2 is a detail plan view, looking in the direction of the interrupted lines.

Figure 3 illustrates a band and two strips 65 connected thereto by the machine.

Figure 4 is a side elevation of some of the parts shown in Figure 1, but in a different position.

Figures 5 and 6 are, respectively, a plan 70 view and a sectional elevation of an alternative or simplified construction, Figure 5 being a view looking in the direction of the arrow 5 above Figure 6, said Figures 5 and 6 illustrating the improvements claimed 75 herein.

The structure shown in Figures 1 to 4, inclusive, is illustrated by the drawings of my application filed July 8, 1919, Serial No. 309,467, and is here shown to aid in illustrating the improvements claimed herein. 80 Referring first, to Figures 1 to 4, inclusive, T is the glue tank, water-jacketed in the usual way. Running in open bearings formed in the sides of the tank T is the supply roller P, partially immersed in the glue, and positively driven the moment the band is pulled, and the swinging and compensating roller W is displaced in the direction of the arrow. Mounted on ledges 85 on each side of the tank T is a stand N having open bearings formed therein to carry the shaft of the gluing roll G. In order to regulate the film of glue that can pass round between the rolls G and P, which are 90 of equal length, the stand N is adjustable along the track 23 by suitable means such as a screw 22, the superfluous glue brought up by the roll P being squeezed out. Fixed 95 on each stand N is a pivot 1 on which swings 100 a frame S normally resting, when the machine is at work, on the projection 2 cast on the stand N. When it is necessary to remove the rolls G and P for cleaning, or to 105 separate the bands from contact with the roll G, in case the machine must remain in-

operative for a time, the whole frame S and its appurtenances is turned over to the position shown in Figure 4.

The arms of the frame S, (one on each side), are rigidly connected by transverse bars 3 and 4, either all cast together or securely bolted together. The guide roller 5 runs freely on pivots 6 fixed in the swinging frame S. Movable along and fixable anywhere on the bar 3 are the guide plates 7, which have forked ends to embrace the rod 8 fixed in projections cast on the frame S, and which serve to keep the band A between the guides 7 when the frame S is turned over. The edging strips 9 pass under a guide roller 10, mounted in bearings 11, and a rod 12 lifts them when the frame S is tilted up. Means, presently to be described, guide the edging strips in their proper relative positions on to the glue roll G, so that the main band A overlaps the margin of the strip or strips 9, a suitable amount as shown in Figure 3. It is obvious that the whole under surface of the strip 9 will be glued by contact with the roller G, but that the underside of the main band A will not be glued where it is superposed on the strip. This is because (see Figure 1) the strips 9 are led in between the roll G and the band A. It is, therefore, necessary to put a film of glue along the margins of the strips 9, on the upper surfaces thereof, before the strips pass under the band A, which film will be as wide as the overlap in order that the strips may adhere to the main band and that the band and the strip or strips will leave the roll G as one united band glued all over the under side. This may be accomplished in the following manner: Bearings 13 are formed in the frame S to receive a shaft B upon which are supplemental gluing rolls C movable longitudinally along and fixable anywhere on the shaft B. When in working position the rolls C are pressed down on the roll G by springs 14 resting on the shaft ends. The width of the surface of each roll C is made about double the amount that the main band must overlap the strips, and they are so adjusted along the shaft B that half their width presses on the upper surface of the margin of the strip, and therefore receives no glue while the other half is exposed, and takes up glue from the roll G. The roll C can be adjusted along the shaft B so as to occupy any desired position relatively to the length of roll G. In order that the glue so taken up by roll C may be transferred to the upper margins of the strip, spreaders 16^a attached to the suitably inclined ends 16 of the arms 15 transfer the glue which has been taken up by each roll C on to that part of the surface of said roll which received no glue from the roll G. Then the glue is taken from roll C by the margin of the strip, as

indicated by the dotted lines in Figure 3. The spreader or transerrer 16^a may be a thin copper blade, resting or trailing on the surface of the roll C, which may be slightly smaller in diameter where it rests on the strip if stout paper is used.

The spreader or transerrer is adjustable in the direction of its length, as by means of a screw 15^a (Figure 2), to vary the width of the glued margin of the strip. 75

Brackets 17 can be moved along and fixed anywhere on the bar 4 and carry pins 18 on which the spreader arms 15 are pivoted, so they can be turned back when it is necessary to remove the shaft B for cleaning. A stud 19, also fixed in the bracket 17, carries a freely running double flanged roll 20. By any suitable means one of the flanges may be adjusted to suit the width of the strip to be used and a pin 21 fixed in the bracket 17 85 serves to keep the strip between the flanges when the frame S is turned over.

In this way by the use of a single gluing roll one or two strips may be properly united to the main band, the whole under surface being suitably glued and all three leave the single gluing roll as one united band, thus greatly simplifying the machine and the work of the operator. 90

Referring now to Figures 5 and 6, which 95 illustrate a simplified construction by the omission of the roll C and the flanged roll 20, and by mounting the transferring spreader or blade close to the periphery of the glue roll G.

In Figure 6, a frame F is mounted to be swung to and from position, the same as frame S in Figures 1 and 4. Said frame F carries or includes rods 30, 31, 32 and 33. Adjustable anywhere along the rod 30 are 105 the guide fingers 36 to position the main band A, which is not shown in Figure 5, to avoid obstruction of parts below. And for the same reason, the strip 9 and its guides 37 and 38 are not shown in quite their proper position in relation to the main band guides 36. It will be understood, however, that they can be each moved on their respective rods so as to lay a strip 9 under the band, as illustrated in Figure 3. It will also be understood that there may be two sets of strip guides when it is required to employ two strips 9. The roll 35 revolves freely on points fixed in the frame F, and the rod 31 prevents disarrangement of the band when 120 the frame F is lifted. Similarly the rod 34 guides the strip or strips 9 and the rod 32 prevents disarrangement thereof relatively to the guides 37, 38, which can be fixed anywhere along the rod 33. On a boss of 125 guide 38 (see dotted lines in Figure 5) is pivotally mounted a finger 39 kept in place longitudinally of the rod 33 by the guide 38 on one side, and by a collar held by a set screw 41 on the other. At the upper end 130

of the finger 39 is a hooked copper blade 40 fixed to, but adjustable on an inclined face on the under side of the finger 39. The copper blade rests on the roll G, and is kept down thereon by the weight of the finger 39, which is quite free on the boss of the guide 38. The blade being inclined to the direction of rotation of the roll G, causes the glue scraped from the roll to run into the pocket formed by 10 the hooked end of the blade 40, and spreads a film of glue along the edge of the strip 9. The width of the film may be regulated by adjusting the blade on the finger 39, so as to project more or less over the edge of the strip. The under edge of the blade at the 15 hooked end is relieved slightly so as to permit the paper to pass below it without raising it off the roll.

The hooked or curved end of the blade 40 is of such substantially semi-circular shape (Figure 5) that its end is located above the edge of the strip 9. Consequently any surplus glue collecting in the pocket formed by 20 said hooked end will be returned on to the glue roll G, and will not escape and form a 25 rib of glue on the strip 9.

The blade is adjustable in the direction of its length, as is the blade 16^a in Figure 2. The screw for securing the blade in its 30 adjusted position is indicated by dotted lines in Figure 5. The adjustment of the blade, and the shape of its hooked end, enables a definite width of glue to be applied to the strip 9, without depositing any surplus 35 thereon.

In banding a box the main band is usually superposed on the strip as the work looks neater than it would otherwise do; but by the present invention the margins of the 40 main band can be glued and the decorative edgings superposed thereon by suitably arranging the guide rolls and spreaders.

I do not herein claim a banding machine having a supplemental roll or rolls C, such 45 as is shown by Figures 1, 2 and 4, because

the same forms the subject-matter of my application, Serial No. 309,467, hereinbefore referred to.

I claim:

1. In a banding machine, a glue-bearing 50 roll, means for directing two strips of sheet material over the roll in overlapping relationship, and a scraper for transferring glue on to a marginal portion of one of said strips to enable the two strips to be adhesively 55 connected, said scraper being adjustable to cause the width of the strip of transferred glue to equal the amount of overlapping of the two strips, the delivery end of said scraper being curved to form a pocket. 60

2. In a banding machine, a glue-bearing roll, means for directing two strips of sheet material over the roll in overlapping relationship, and means for supplying glue to the upper surface of the underlying strip, 65 said means including a scraper adjustable according to the width of the overlapping portions of the strips, the delivery end of said scraper being curved to form a pocket.

3. In a banding machine, a glue-bearing 70 roll, means for directing two strips of sheet material over the roll in overlapping relationship, and means for supplying glue to the upper surface of the underlying strip, 75 said means including a scraper having its delivery end forming a pocket, the edge of which extends to a point to return surplus glue over the edge of said underlying strip.

4. In a banding machine, a gluing roll, 80 means for transferring glue from said roll to the upper side of a strip of paper or similar material passing thereover, said means comprising a scraper adjustably mounted to accurately determine the width of the strips of transferred glue, the delivery end of said 85 scraper being substantially semicircular to return surplus glue onto said roll.

In testimony whereof I have affixed my signature.

JOHN WILLIAM NASMITH.
